UNITED STATES PATENT OFFICE

2,569,565

CASEMENT WINDOW OPERATOR

Noble M. Hiser, Tucson, Ariz.

Application May 17, 1950, Serial No. 162,463

3 Claims. (Cl. 268—118)

1

This invention relates to a window, and more particularly to a manually-operable mechanism for operating a window.

The object of the invention is to provide a mechanism which is adapted to be manually operated in order to open and close a window.

Another object of the invention is to provide a window-operating mechanism which includes an actuating handle that can be pivoted or moved to back out of the way when not in use, the parts of the mechanism being interchangeable so that the mechanism can be used for windows which open from either the left or right side.

Another object of the invention is to provide a window-operating mechanism which is extremely simple and inexpensive to manufacture.

Other objects and advantages will be apparent during the course of the following description.

In the accompanying drawings forming a part of this application, and in which like numerals are used to designate like parts throughout the same:

Figure 1 is a fragmentary top plan view of the window-operating mechanism of the present invention, with the window and frame being shown in section;

Figure 2 is a fragmentary, horizontal sectional view taken through the window-operating mechanism of the present invention;

Figure 3 is a view similar to Figure 2, but with the arm, handle and dogs removed;

Figure 4 is a fragmentary, sectional view through the operating mechanism, showing the position of the parts during the initial movement of the handle;

Figure 5 is a view similar to Figure 4, but showing the next positions of the parts;

Figure 6 is a view similar to Figure 5, but with the actuating arm and dogs attached;

Figure 7 is a side elevational view of the window-operating mechanism, with parts broken away and in section;

Figure 8 is a sectional view taken at right angles to the Figure 7 view;

Figure 9 is a fragmentary, longitudinal, sectional view showing the coil spring being compressed;

Figure 10 is a horizontal, sectional view showing the spindle, casing and handle.

Referring in detail to the drawings, the numeral 20 designates a portion of a window frame which is provided with a slot or opening 21 therein, Figure 1. A window 22 is hingedly connected to the frame 20, the window 22 being mounted for opening and closing movement with respect to the window frame 20. The window 22 includes a

2

glass pane 23, there being a groove or channel 24 arranged in the bottom of the window 22 for a purpose to be later described. The window 22 is hingedly connected to the frame 20 by means of hinge parts 26 which are pivotally connected to corresponding hinge parts 25 by a pin 27. The hinge parts 25 are secured to the frame 20, while the hinge parts 26 are secured to the window 22.

10 The present invention is directed to a manually-operable mechanism for opening and closing the window 22, and the mechanism includes a hollow housing 28 which is provided with a transverse flange 29, and a plurality of securing elements, such as rivets 30, project through the flange 29 and into the frame 20 for connecting the housing to the frame.

The housing 28 may be fabricated of any suitable material, and the housing 28 includes a top wall 31, Figure 8, and a bottom wall 32, there being an end wall 33 arranged between the top and bottom walls. The end wall 33 is provided with an elongated slot 34, Figure 7. Rotatably supported in the housing 28 and extending between the top and bottom walls thereof is a hollow, cylindrical spindle 35. An actuating arm 36 is keyed, as at 37, Figure 7, to the spindle 35, so that as the spindle 35 rotates, the actuating arm 36 rotates therewith. The other end of the arm 36 is provided with a bushing 38 which slidably projects in the groove 24 in the bottom of the window 22, so that this movement of the actuating arm 36 causes opening and closing movements of the window 22. The inner end of the arm 36 is provided with an enlarged body portion 39, there being a central opening 40 arranged in the body portion 39, Figure 6, and the opening 40 snugly receives therein the spindle 35. Arranged along one side of the body portion 39 is a plurality of spaced teeth or serrations 41, while arranged along the opposite side of the body portion 39 is a similar plurality of teeth 42 for a purpose to be later described.

45 Slidably projecting through the slot 34 in the housing 28 is a hollow casing 43, Figure 10. The casing 43 is provided with a channel 44, there being an opening 45 arranged in the inner end of the casing 43 for rotatably receiving therein the spindle 35. An actuating handle 46 is reciprocably or slidably mounted in the channel 44 of the casing 43, and the inner end of the handle 46 is shaped to define a finger or lug 47, the finger 47 being mounted for movement into and out of registry or engagement with an opening 48 that is arranged in the spindle 35. Thus, when the

50

finger 47 is projecting through the opening 48, rotation of the handle 46 will cause rotation of the spindle 35, but when the finger 47 is retracted from the opening 48, the handle 46 and casing 43 can freely rotate about the spindle 35. By means of this construction, the handle 46 and casing 43 can be swung or moved to an out-of-the-way position when not being used.

Arranged in the housing 28 is a washer 49, Figure 2, and the washer 49 is provided with a large opening 50 for loosely receiving therein the spindle 35. The washer 49 is interposed between the casing 43 and the arm 36, Figures 7 and 9.

A pin 51 pivotally connects one end of the arm 36 to the washer 49, there being a cutout or split 52 arranged in the washer 49. Carried by the inner end of the handle 46 is a pin 53 which is mounted for movement into and out of engagement with the cutout 52 in the washer 49. The pin 53 slidably projects through a slot 54 in the upper surface of the casing 43. Thus, as the handle is reciprocated back and forth in the casing 43 by means of the knob 55, the pin 53 can be moved into and out of engagement with the cutout 52. The handle 46 is provided with a cutaway portion or recess 56, Figure 10, and a lug 57 projects upwardly from the bottom of the casing 43 and into the recess 56. A coil spring 57' is interposed between the lug 57 and the handle 46, and the coil spring 57' serves to normally urge the finger 47 into the opening 48 and the pin 53 into the cutout 52.

A dog 58 has one end pivotally connected to the top wall 31 of the housing 28 by a pin 60, Figure 2, and the dog 58 includes a pointed end 59 that is mounted for movement into and out of engagement with the teeth 41 of the body portion 39. A spring member 61 normally urges the pointed end 59 of the dog 58 into engagement with the teeth 41. Carried by the dog 58 is a pin 62, and the pin 62 is adapted to be engaged by the washer 49, whereby the pointed end 59 can be moved out of engagement with the teeth 41. Arranged on the opposite side of the housing 28 is a similar dog 63 which includes a pointed end 64 that is mounted for movement into and out of engagement with the teeth 42. The dog 63 is normally urged into engagement with the teeth 42 by a spring member 66, the dog 63 being pivotally connected to the top wall 31 of the housing by a pin 65. Carried by the dog 63 is a pin 67 which is adapted to be engaged by the washer 49, whereby the dog 63 can be moved out of engagement with the teeth 42 so as to permit turning movement of the arm 36.

The pointed ends of the dogs 58 and 63 are normally urged into engagement with the teeth 41 and 42 of the arm 36 by means of the spring members 61 and 66. Thus, it is impossible to turn the arm 36 and the window 22 unless the dogs 58 and 63 have been urged out of the respective teeth on the arm 36.

To open or close the window, the user merely swings the manual handle 46 from its dormant position, as indicated by the dotted lines in Figure 1, away from the frame 20 until the finger 47 enters the hole 48 in the spindle 35. At the same time, the pin 53 is engaged in the cutout or notch 52 provided for it in the washer 49. The finger 47 is made so that it is a loose fit in the hole 48, whereby the arm 36 can be moved slightly before the spindle 35 moves. When the window is being closed, the handle 46 is moved to the right. At the same time, the washer 49, which is pivoted on the pin 51 and which has

its edges in contact with the studs or pins 62 and 67 of the dogs 58 and 63, moves to the left, forcing the dog 58 out of the teeth 41 on the arm 36 and thus permitting the arm 36 to be moved to the left. As soon as the pressure is taken from the arm 36, both dogs 58 and 63 will again engage the teeth on the arm 36 whereby accidental rotation of the arm will be prevented. When the window is being opened, the handle 46 is moved to the left, whereby the dog 63 will be moved out of the teeth 42 so that the arm 36 can be moved to the right.

When the window has been set at a desired position, the handle 46 is pulled outward, disengaging the pin 47 from the hole 48 in the spindle 35. This permits the handle 46 to be swung over against the window frame out of the way.

From the foregoing it is apparent that a window-operating mechanism has been provided wherein the handle can be shoved back against the window frame when not in use. Also, the locking dogs are automatically released when the window is being opened or closed. Also, the cost of manufacturing the window-operating mechanism is extremely small.

I claim:

1. In combination, a window frame, a window hingedly connected to said frame, a manually-operable mechanism for causing opening and closing of said window, said mechanism comprising a hollow housing secured to said frame and including a top wall and a spaced parallel bottom wall, a hollow cylindrical spindle rotatably supported by said top and bottom walls, there being an opening in said spindle intermediate its ends, an actuating arm having one end connected to said spindle and its other end pivotally connected to said window, there being a slot arranged in said housing, an elongated hollow casing slidably projecting through said slot and having its inner end rotatably connected to said spindle, a handle slidably arranged in said casing and provided with a finger for movement into and out of the opening in said spindle, a coil spring for normally urging said finger into said opening, a washer loosely mounted on said spindle and pivotally connected to said arm, there being a cutout in said washer, a pin projecting from said handle and mounted for movement into and out of the cutout in said washer, a plurality of spaced teeth arranged on each side of said arm, and a pair of dogs pivotally connected to the top wall of said housing and mounted for movement into and out of engagement with the teeth on said arm.

2. The apparatus as described in claim 1, and further including spring members for normally urging said dogs into engagement with the teeth on said arm.

3. In combination, a window frame, a window hingedly connected to said frame, a manually operable mechanism for causing opening and closing of said window, said mechanism comprising a housing secured to said frame and including a top wall and a bottom wall, a hollow spindle rotatably supported by said top and bottom walls, there being an opening in said spindle, an actuating arm having one end connected to said spindle and its other end pivotally connected to said window, there being a slot arranged in said housing, a hollow casing slidably projecting through said slot and having its inner end rotatably connected to said spindle, a handle slidably arranged in said casing and provided with a finger for movement into and out of the opening

in said spindle, a coil spring for normally urging said finger into said opening, a washer loosely mounted on said spindle and pivotally connected to said arm, there being a cutout in said washer, a pin projecting from said handle and mounted for movement into and out of the cutout in said washer, a plurality of teeth arranged on each side of said arm, and a pair of dogs pivotally connected to the top wall of said housing and mounted for movement into and out of 10 engagement with the teeth on said arm.

NOBLE M. HISER.
